UNITED STATES PATENT OFFICE.

CLARENCE H. HAPGOOD, OF TOLEDO, OHIO, ASSIGNOR TO TOLEDO SCALE COMPANY, OF TOLEDO, OHIO, A CORPORATION OF NEW JERSEY.

DESIGN FOR A SCALE CASING.

Application filed September 8, 1922. Serial No. 3,658. Term of patent 14 years.

To all whom it may concern:

Be it known that I, CLARENCE H. HAPGOOD, a citizen of the United States, residing at Toledo, in the county of Lucas and State of Ohio, have invented a new, original, and ornamental Design for Scale Casings, of which the following is a specification, reference being had to the accompanying drawing, forming a part thereof.

The figure is a front elevation of a scale casing showing my new design.

I claim:

The ornamental design for a scale casing as shown.

CLARENCE H. HAPGOOD.
